CLAIM

The ornamental design for top surface of a powder puff handle, as shown and described.

DESCRIPTION

FIG. 1 is a perspective view of a top surface of a powder puff handle showing my new design;

FIG. 2 is a top plan view thereof; and,

FIG. 3 is a side elevational view.

The broken line showing of the device for applying powder is for illustrative purposes only and forms no part of the claimed design.

FIG. 1

FIG. 2

FIG. 3
